(57) **CLAIM**

The ornamental design for a steering wheel for vehicles, as shown and described.

DESCRIPTION

FIG. 1 is a front perspective view of a steering wheel for vehicles, showing a first embodiment of our new design;
FIG. 2 is a front view thereof;
FIG. 3 is a rear view thereof;
FIG. 4 is a top view thereof;
FIG. 5 is a bottom view thereof;
FIG. 6 is a right side view thereof;
FIG. 7 is a left side view thereof;
FIG. 8 is a back perspective view thereof;
FIG. 9 is a front perspective view of a steering wheel for vehicles, showing a second embodiment of our new design;
FIG. 10 is a front view thereof;
FIG. 11 is a rear view thereof;
FIG. 12 is a top view thereof;
FIG. 13 is a bottom view thereof;
FIG. 14 is a right side view thereof;
FIG. 15 is a left side view thereof; and,
FIG. 16 is a back perspective view thereof.
